TRAIN BOARD

Stephen Y. McGiffert, Fort Sill, Okla., and Hugh P. Adams, Fort Sam Houston, Tex.

Application January 23, 1932, Serial No. 588,356, and in Germany October 2, 1931

24 Claims.

(Cl. 35—12)

We have filed application for Letters Patent hereon in Germany on October 2, 1931, application Number M. 117,098 XI/72f.

This invention relates to apparatus for training officers in the conduct of field artillery fire and represents an improvement upon previously known methods such as blackboard practice and previously known terrain boards. It aims to provide apparatus which will reproduce on a miniature scale but with a lifelike appearance and with mathematical accuracy the firing of an actual battery under real conditions.

This application is a continuation in part of our application Serial No. 345,717 for U. S. Letters Patent, filed March 9, 1929, since issued as Patent No. 1,843,237, February 2, 1932.

Other objects are to provide such an apparatus which may be mechanically operated correctly by a person not acquainted with the ballistics, gunnery and the principles of field artillery firing, under the direction of a student in such a manner that the student, who represents the commander of a battery, does not need to give any attention to the operator other than preliminary instructions. Further aims are the provision of apparatus of this sort characterized by such size and weight as to be portable, by strength and simplicity of construction and reasonable cost of manufacture. Further aims and advantages of the invention will appear as the description proceeds. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principles of the invention may be used.

In said annexed drawings:

Fig. 1 is a perspective view of the assembled apparatus; Fig. 2 is a diagrammatic plan corresponding to Fig. 1 illustrating the arrangement of the apparatus for use to represent axial firing; Fig. 3 is a front view showing the appearance of the apparatus to the student when arranged to represent lateral observation; Fig. 4 is a diagrammatic plan corresponding to Fig. 3; Fig. 5 is a front elevation showing the appearance in a set-up different from that of Fig. 3; Fig. 6 is a diagrammatic plan corresponding to Fig. 5; Fig. 7 is an enlargement in front elevation of a detail of Fig. 1; Fig. 8 is a plan of the principal mechanism; Fig. 9 is a side elevation on the line 9—9

of Fig. 8; Fig. 10 is an elevation on the line 10—10 of Fig. 8; Fig. 11 is a rear elevation on the line 11—11 of Fig. 8; Fig. 12 is a front view of the burst representing means, indicating an air burst; Fig. 13 is a view of the same means, representing an impact burst; Fig. 14 is a view from the right side of Fig. 12; and Fig. 15 is a view from the right side of Fig. 13.

Before proceeding to a detailed description of the mechanism it may be explained that the apparatus provides a miniature landscape, known as the terrain, on which a miniature target is placed, the landscape being suitably screened and illuminated so as to present to the eye of an observer the appearance of an actual landscape at distances such as are used in artillery firing. Means are provided, above the terrain and concealed from the student, for lowering into the student's field of vision a bead, hereafter called a burst bead, the appearance of which realistically imitates that of the burst of an artillery projectile at the represented distances. The lowering means are actuated by an operator so that the burst bead is seen in the student's field of vision, and in relation to the miniature target in the manner that an actual projectile burst would appear in relation to an actual target.

Referring now particularly to Fig. 1, the apparatus comprises a base 1 to which a screen 2 is immovably secured. A terrain board 3 is pivoted to this base near the center of the terrain board, the pivot being concealed. Short sides 4 and a back 5 are rigidly attached to the board 3. Due to this pivoting the terrain board can be moved, if desired, from the straight position shown in Figs. 1 and 2 to such positions as are shown in Figs. 4 and 6, or others. The screen 2 is of a height to conceal from the student all of the apparatus for lowering the burst bead 6 into view, and the student looks through an opening 7 practically along the level of the terrain so as to have the effect of looking at a distant landscape, as shown in Figs. 3 and 5. The terrain is illuminated by suitable means behind the screen, such as electric lights 8 in the corners of the screen 2 and shielded as at 9 so that the light does not shine toward the student. A scale 10 may be conveniently provided on the front of the base 1 to measure the horizontal angle between the axis of the terrain and the axis of the base. Field artillery observation telescopes and field glasses are usually provided with a mil scale in the field of view to measure the lateral deviation of the bursts. This is imitated in the present invention by transparent plates 11, known as reti-

cules, placed on the lower edge of the opening 7, one for each observer, Figs. 3 and 5. These reticles are marked with mil or other angular scales, such as 12, 13 and 14, Fig. 7, whereby the observer can measure deflections, as explained hereafter. The different sizes of scales are for use at different observer-target distances.

The side walls 4 of the terrain board support parallel horizontal range arms 15 which are graduated bars of about the same length as the terrain board, the bars being just short enough to swing with the terrain clear of the screen 2 when the apparatus is positioned as shown in Fig. 4, for example. The side walls 4 are made much shorter than the terrain and are sloped back as shown so that the terrain may be seen from the side through the opening 7 when in such positions as that of Fig. 4. It will be seen that the range arms 15 are always fixed in relation to the terrain. A deflection bar 16 is transversely disposed above the terrain, being carried at either end by shoes 17, 18 when resting on the range arms 15. The deflection bar is graduated, as shown in Fig. 8, in mils according to the angle subtended at the gun which is the base piece.

An indicator assembly 19, which is the immediate means used in conjunction with the deflection bar representation of bursts, is slidably mounted on the deflection bar. A sheaf block 20, also supported by the deflection bar, may also be placed at any position along the deflection bar by hooks 21 and clamped there as by a set screw 22 or other means. Indicators 23, one for each gun of the battery represented, are disposable along the sheaf block according to the mil scale shown on the block in Fig. 8 to show the spread of bursts due to the deflections of the individual guns. These indicators 23 are accordingly set in accordance with the commands for dispersion of fire to indicate the several successive positions of the indicator assembly 19 for the successive rounds from several supposed guns.

Referring now to the details of the apparatus, the range arms are graduated, as best seen in Fig. 9, either in yards, meters or otherwise in proportion to the scale of the terrain. The zero point of the graduations is at a hypothetical gun position well in front of the apparatus. Such a gun position is indicated at 91, Figs. 2, 4 and 6. The shoes 17 and 18, which carry the deflection bar, are to be set along the range arms at the indicated ranges, each shoe having an index finger such as 24 which is in transverse alignment with the basic position of the burst head 6.

For the purpose of varying the position of the burst head 6 relatively to the target to simulate the dispersion of bursts in actual practice due to probable errors of matériel, the shoes 17 and 18 are each made with a convex bottom surface as indicated at 25 in Fig. 8. Inasmuch as the deflection bar 16 is formed integrally with or rigidly attached to these shoes, rocking of the shoes will tilt the indicator assembly 19 forward and back from the vertical. The forward position is shown in Fig. 1. When the burst head 6 is dropped, as described hereafter, if the assembly 19 is tilted at the time, the burst head will drop either behind or in front of the exact range at which it would fall on a vertical drop. To prevent the shoes 17 and 18 from sliding along the range arms during rocking, each is provided with a friction surface, this being conveniently accomplished by a flat rubber band such as 26 on the shoe, forming in effect a flat rubber tire. Of course other friction surfaces could be used.

A guide member known as a disperser arm 30 is associated with the shoe 18. This disperser arm 30 is made in the form of a plate disposed along and just outside its respective range arm 15. This plate is pivoted as at 31 to the shoe 18 and has an upstanding ear 32 above the pivot 31. A tension spring 33 connects the front end of the shoe 18 and the ear 32, tending to pull up the rear end of the disperser arm. The rear end of the arm 30 has a lowered side bracket 34 the rear of which ends in an upstanding hook 35 turned in to engage the top of the range arm 15. The bracket 34 carries a rotatable element 40, known as a disperser, on a vertical spindle 41. In the preferred form, here shown, this disperser is a cylinder with a notched spiral flange 42 thereon. An outwardly directed lug 43, Fig. 8, on the rear end of the shoe 18, strikes the flange 42 and so limits the angle between the shoe 18 and the disperser arm 30. The shoes 17 and 18 are always rocked to the rear by the operator, as explained hereafter. The contact of the hook 35 with the top of the range bar 15 and of the lug 43 with some point on the flange 42 stop this rocking movement. Since the angle between the shoe 18 and the disperser arm 30 is set by the point on the spiral 42 at which the lug 43 stops, it follows that the contact between the lug 43 and spiral 42 governs the inclination to which the indicator assembly 19 can be tilted. The spiral 42 is so laid out that its middle point holds the shoe 18 horizontal and consequently holds the indicator assembly 19 vertical. The fall of the burst head 6 either in front of, or at, or behind the vertical position of the true range depends on the angle of the indicator assembly. The spiral curve of the flange 42 represents the dispersion of actual bursts in accordance with accepted ballistic tables and its coaction with the lug 34 causes the phenomenon of dispersion in range to be correctly represented, as will be described hereafter.

The indicator assembly 19 is best seen in Figs. 8, 10 and 11. This assembly comprises a base 50 held to a snug sliding fit on the deflection bar 16 by any suitable means such as a spring leaf 51 whereby the indicator assembly will stay in any position to which it is set along the deflection bar and will not have any rocking motion independent of the bar. The base 50 which is preferably of cast metal construction includes an upright plate 52 extending from below and behind the deflection bar 16 to a point above and forward of that bar, affording a long firm upwardly inclined base for a diagonally movable plate 55 of generally triangular outline, known as the upper indicator. This upper indicator plate 55 is also preferably a casting from the rear of which the standard 56 rises. The lower diagonal surface of the upper indicator 55 carries an index, shown in Fig. 10, which is read against the index point indicated by the arrow, and suitable means are provided for clamping the indicator 55 at any given index reading along the base, the preferred means being a slot 100, Fig. 10, in the base 52, parallel to the diagonal edge, in which a clamp screw 57 travels. A block 60 slides up and down between the standard 56 and an upright finger 61. This block is marked with an index, Fig. 10, to read against a scale on the finger 61. A clamp screw 62 fastens this block along the scale. The block 60 includes a bracket 63 at one side from which there depends on a spindle a cylinder 64, called a variator, similar to the disperser 40 and likewise including a notched spiral flange 65.

The spiral 65 is a mathematical curve representing height burst dispersion as given by ballistic tables, therefore a different curve from the spiral 42 on the disperser 40. The standard 56 has 5 top and bottom side extensions 66 and 67 respectively, between which a guide wire 68, parallel to the side of the standard 56, extends, as best seen in Fig. 11. A collar 70 is movable down the guide wire 68 by a thumb piece 71, but is normally 10 held at the top by a spring 72, the downward motion of which is guided by an upright finger 73 behind the standard 56. A fork 74 sliding on one edge of the standard 56 keeps the collar 70 from turning around the wire 68. On the side away 15 from the standard 56 the collar is vertically pierced to receive the upper end of a wire 75, the lower end of which suspends the burst bead 6. The wire 75 is clamped by a screw 76. This arrangement permits the burst bead 6 to be faced in 20 any direction, and is necessary to allow the bead 6 to be faced toward the observer in such situations as that of Fig. 4. The bead wire passes down through a guide 77 on the side of the bottom extension 67, and is stopped at the bottom of its 25 motion by a lug 78 on the collar 70 striking the flange 65. When percussion firing is to be represented the block 60 is removed. In that instance the bead 6 always goes entirely down on the terrain, as in Fig. 15.

30 The location of the axis of rotation in the burst bead 6, is eccentric, in such a way that the center of gravity of the burst bead causes it to hang at the limit of its rotation in one direction, when freely suspended from the wire 75, as in Fig. 14. One side of the front face of the bead is recessed as at 79 and the bottom of the wire 75 is bent to pivot the bead at the side of this recess. Thus the back of the recess limits the downward position of the bead when suspended in the air as shown in Fig. 14. The bottom and back of the burst bead are so rounded that when the bead is lowered onto the terrain or other object and is no longer freely suspended the weight of the bead and the pressure of the 45 wire 76 downward rocks the burst into the position of Fig. 15.

When the burst bead 6 hangs freely suspended from the wire 75 when viewed at the same level and from the front the face 80, the color of the 50 smoke of an air burst, is visible, as in Fig. 12, but when the bead rests on some object, the bottom 81, dark brown, the color of an impact burst, is visible, as in Fig. 13.

55 Thus when the apparatus is used to represent firing with projectiles having time fuzes, or combination time and percussion fuzes, when the point of burst is in the air, the burst bead appearance is similar to an actual air burst, but when the point of burst is on or below the ground, 60 the burst bead appears as an actual percussion burst upon the surface of the ground.

65 It will of course be appreciated that different beads may be used to represent different appearances. For example, the face 80 is colored the same as the smoke produced by the burst of actual projectiles which it is intended to simulate, and the face 81 is colored to represent the characteristics of the ground of any particular region as to which it is desired to give training.

70 The appearance of soil thrown up will of course be somewhat modified by the smoke of the explosion. In practice the main distinction of appearance between an air burst and a graze burst is that the air burst is light colored and 75 the graze burst much darker. However, if it is

desired to go further into details of color in using the train board, different appropriate beads could be used.

Consequently one train board with a suitable assortment of beads can be used to represent the firing of ammunition giving various smoke colors and on various ground, each bead representing by one face the air burst for some particular explosive and by the other face the graze burst appearance due to soil conditions (or water) in the region represented.

For problems in some kinds of fire it is necessary to indicate on the terrain arbitrary heights to which bursts may be referred. In actual practice this would be accomplished by setting cross hairs on a transit or other observing instrument. For this purpose on the train board one or more stands 85 are provided, each consisting of a base supporting a vertical wire on which a bead 86 is held by friction at any desired height. This stand assembly is known as a high burst wire.

In the operation of the train board, the device shown in Fig. 1 is set on a table or other suitable support and the student, representing 100 the battery commander, or other officer conducting the fire, sits in a chair or on a stool, the relative heights of the train board and of the student's eye being such that the student looks just over the reticule 12 thus getting the 105 effect of a distant landscape through a field glass as shown in Figs. 3 and 5. The plan of the general set-up for axial fire is shown in Fig. 2 and variations for other types of fire are shown in Figs. 4 and 6. A variety of other arrangements 110 are possible, simulating all the conditions under which field artillery may fire in target practice or in actual warfare. For moving targets, strings may be led through eyes such as 87 on edges of the terrain, and a second operator moves the target 115 by pulling the string, while the first operator works the train board mechanism. In Figs. 2, 4 and 6, 90 represents the position of the student, 91 represents the position of the gun and 92 represents the position of a lateral observer, 120 as necessary in certain types of firing. In firing problems wherein the battery commander is at the battery, the positions 90 and 91 of course coincide. It is not necessary to use a miniature representation of a gun, although this may be 125 done if desired as a matter of convenience in visualizing the conditions of the problem. The target 93 is set on the terrain board 3, using for the target some object of approximately proportional size in accordance with the assumed range. 130 Burnt match heads make convenient targets. Movable landscape features on appropriate scale may be placed on the terrain and the target may be placed with respect to these, in a variety of combinations such as would be met with in 135 reality. The distances of the student from the target and of the gun from the target are measured upon the same proportionate scale as the graduations of the range arms 15. Consequently, all distance relations are in the same relative 140 proportions as would be the case in actuality and all angular relations are the same as would really exist.

To fire any problem the student places himself in the appropriate position 90 and an operator 145 of the train board stands beside it where he can conveniently reach the indicator mechanism 19. In moving target problems it is necessary to have a second operator to pull the strings by which the targets are moved. As an example of 150

the operation, a problem in lateral observation with the gun to the right of the observation post, as shown in Fig. 4, will now be described. The terrain 3 is swung around relatively to the screen 2 for the reason that the range bars 15 must always be parallel to the line of fire in order to give a truthful representation. At the same time it is always necessary that the observer look over the reticule 11 in the opening 7. The burst bead wire 75 is turned so that the bead 6 will face the student so as to appear to him as in Figs. 12 and 13.

The target 93, Fig. 4, having been placed on the terrain, the appearance to the observer will be as shown in Fig. 3. This figure makes it clear why the sides 4 cannot extend too far forward. The distance from the student's eye to the aperture 7 being known, the reticule 11 is set in place with the appropriate scale 12, 13 or 14 uppermost and centered. The student gives the commands for opening fire at an assumed approximate range in accordance with established practice, indicating the range, deflection, angle due to assumed difference in level between gun and target (known as the angle of site), fuze setting governing the intended height of burst, and any other firing data that would be used in actual firing. The operator lifts the shoes 17 and 18 slightly off the range arms 15, and sets them down with the index 24 at the commanded range, moves the indicator base 50 on the bar 16 to an arbitrary deflection setting, sets the block 60 by its scale according to the angle of site, sets the upper indicator 55 along its scale to represent the given fuze corrector setting. He then rocks the arm 18 forward with his left hand, pressing the arm 34 down with his thumb (against the pull of the spring 33) until the hook 35 stops on top of the bar 15. Thus the lug 43 is elevated away from the flange 42, so that the operator can spin the disperser 40 with his right hand. He so spins it and also spins the variator 64. He then rocks the rear end of the shoe 18 downward until the lug 43 stops on the flange 42, in which position the angle of the assembly 19 (or, more strictly, of the wire 75) is governed by the point along 42 at which 43 rests, and that point, due to the mathematical construction of the flange 42, varies on successive spins according to the variation in distribution of successive rounds in actual firing.

The operator now presses down the thumb piece 71 until it is stopped by the variator 64 or by the burst bead 6 striking the terrain 3, as the case may be, according to where the variator has stopped in its spin. After about two seconds, the length of time the smoke of an actual burst would remain visible, the operator releases the thumb piece and the spring snaps the bead up out of view.

The different stopping points of the variator between spins give a mathematically accurate variation between heights of successive drops of the bead 6. Consequently the combined effects of the disperser and variator, imposed upon the several scale settings cause the bead to represent faithfully the performance of real ammunition, both as to predetermined factors and as to chance factors. Therefore the student, looking over the reticule scale at the momentarily visible bead, makes the same quick estimate of errors in his firing commands as he would in actual firing, and gives the appropriate corrective commands. The operator makes the corresponding new settings of the train board elements and again drops the bead. This proceeds until the firing data is cor-

rectly worked out for the given problem, or in other words, until the completion of the adjustment of all of the elements of fire for each of the guns. Fire for effect may likewise be represented by the train board.

The firing of only one gun has been described above. To represent several guns the sheaf block 20 is used in conjunction with the deflection bar 16. The sheaf block can be made in any size according to the number of guns the fire of which is to be represented. Fig. 8 illustrates a sheaf block to represent a four gun battery, having one indicator 23 for each gun, movable along the lines marked 1, 2, 3 and 4, corresponding to the gun members. The indicators are set along the sheaf block mil scale to indicate the planes of fire of the respective guns, the plane of fire being the plane in which the trajectory of the gun lies. The operator initially sets the indicators 23 arbitrarily for either diverging, parallel, converging or cross fire, and represents such fire by setting the indicator assembly 19 to bring the burst bead wire 75 opposite the indicators successively, in the firing order of the battery, before dropping the bead each time. As commands are given which alter the spread of the sheaf, the operator moves the indicators accordingly. It will be understood that the sheaf block is positioned on the deflection bar in the proper relation which the sheaf would bear to the target according to the commands given.

In using the train board to represent high burst transfer problems, Figs. 5 and 6, one reticule is used for each of the two student observers, 91 and 92, and two high burst wires 85 are used to mark the respective lines of observation, each with its bead 86 set at the height required above the unseen target. Each observer looks over the center of his respective reticule at his own bead 86, and observes the successive appearances of the burst bead 6 as to height and deflection with respect thereto, just as he would observe actual high bursts through a transit clamped at the corresponding horizontal and vertical setting. The combined observations are used in determining the commands which the operator sets off on the train board elements, all in a manner which will be readily understood by artillery officers.

It is apparent from the foregoing examples how the principles of operation of this invention may be applied to represent other tactical situations than those described.

It is also apparent that although the invention is particularly shown and described as applied to field artillery training, its features, so far as appropriate, may be used in the training of other types of artillery.

We claim:

1. In a device for giving instruction in the conduct of artillery fire, in combination with means representing a terrain and including a pair of parallel range arms, means mounted on said arms comprising a cross-bar and a shoe having a convex bottom surface mounted on each end of said cross-bar, said shoes having their convex surfaces mounted to rock on said arms, respectively, means for rocking said shoes on said arms and means for limiting the amplitude of such rocking motion variable according to ballistic probabilities of range dispersion.

2. In a device for giving instruction in the conduct of artillery fire, in combination with means representing a terrain and including a pair of parallel range arms, means mounted on said arms comprising a cross-bar, a shoe having a convex

- bottom surface mounted on each end of said cross-bar, said shoes having their convex surfaces mounted to rock on said arms, respectively, and friction means between said arms and said 5 respective shoes.
3. In a device for giving instruction in the conduct of artillery fire, in combination with means representing a terrain and including a pair of parallel range arms, means mounted on said arms 10 comprising a cross-bar, a shoe having a convex bottom surface mounted on each end of said cross-bar, said shoes having their convex surfaces mounted on said arms, respectively, friction means between said arms and said respective 15 shoes, means for rocking said shoes on said arms and means for limiting the amplitude of such rocking motion variable according to ballistic probabilities of range dispersion.
4. In a device for giving instruction in the conduct of artillery fire, in combination with means 20 representing a terrain, a cross-bar movably supported adjacent said means, a member slidably mounted upon said cross-bar, a wire suspended from said member and vertically reciprocable with respect thereto, a single bead simulating a plurality of appearances of a projectile burst mounted at the lower end of said wire.
5. In a device for giving instruction in the conduct of artillery fire, in combination with means 25 representing a terrain, a graduated cross-bar movably supported adjacent said means, a slide on said cross-bar, a sheaf-block slidably mounted on said cross-bar, a scale on said block, a plurality of elements adapted to be positioned upon 30 said block in accordance with said scale each to represent a specific piece of a battery, said slide being movable into registry with any one of said elements, and a single means simulating a plurality of appearances of a projectile burst suspended from said slide and movable into close 35 proximity with the terrain.
6. In a device for giving instruction in the conduct of artillery fire, means representing a terrain, a member movable by an operator relative 40 to said terrain in response to a student's orders, a single means carried by said member for indicating automatically either "graze bursts" or "air bursts" relative to the terrain, and means for governing the movement of said indicating means 45 in accordance with the proper ratio of "air bursts" to "graze bursts" for any given height of burst setting.
7. In a device for giving instruction in the conduct of artillery fire, a bar, a slide having a bifurcated base adapted slidably to receive said bar, a 50 rod mounted on said slide, a handle member slideable on said rod, a wire suspended from said handle member, and means carried by said wire simulating the appearance of the burst of an artillery projectile, said handle being adapted to move said wire to position said simulating means in given relation to said slide and said rod.
8. In a device for giving instruction in the conduct of artillery fire, means representing a terrain, and means associated with said first-mentioned means for indicating the longitudinal, lateral, and elevational location with respect to 55 said terrain of the bursts of projectiles thrown from a hypothetical piece at any given aim, said last-mentioned means including a single bead simulating the appearance of a projectile burst either in air or on graze.
9. In a device for giving instruction in the conduct of artillery fire, means representing a terrain, 60 a screen adjacent an edge of said means between said means and the student's eye, lights on the side of said screen towards the terrain-representing means, means including said screen shielding the student's eye from said lights, said screen being formed with a sighting aperture, and transparent movable means associated with said aperture and carrying indexes adapted to indicate to the student lateral displacement of objects on the terrain from his line of sight.
10. In a device for giving instruction in the conduct of artillery fire, means representing a terrain, a screen adjacent an edge of said means between said means and the student's eye, said screen being formed with a sighting aperture, and a transparent movable plate associated with said aperture and carrying a plurality of indexes placed on separate parts of the edges of said plate, each index being adapted to indicate to the student lateral displacement from his line of sight of objects on the terrain according to an assumed observer-target distance coordinated with such index.
11. In a device for giving instruction in the conduct of artillery fire, means representing a terrain, a screen adjacent an edge of said means between said means and the student's eye, said screen being formed with a sighting aperture, and transparent movable means associated with said aperture and carrying a plurality of indexes of different scales adapted to indicate to the student lateral displacement of objects on the terrain from his line of sight, the scale of each index being proportional to a predetermined distance between the student's eye and said transparent means.
12. In a device for giving instruction in the conduct of artillery fire, means representing a terrain, a screen intercepting the student's vision of said means, said screen being formed with a sighting aperture through which said means are visible in perspective, a transparent plate mounted to slide transversely in said aperture, and a plurality of scales of angular measurement on said plate, said scales being of different sizes but each so proportioned that at a given distance from the student's eye to said plate the angle subtended at the eye has the same angular value.
13. In a device for giving instruction in the conduct of artillery fire, generally horizontal means representing a terrain and revolvable in its own plane, a member movable above said plane into predetermined positions representing various factors governing the fall of a projectile in field artillery fire, said member having a face of distinctive appearance, means for lowering said member into approximately the plane of the terrain, and means for maintaining said member in a position rotated about a vertical pivot in equal amount but opposite direction to the rotation of said terrain-representing means.
14. In a device for giving instruction in the conduct of artillery fire, in combination with means representing a terrain, a cross-bar movably supported adjacent said means, a member slidably mounted upon said cross-bar, an element 140 simulating the burst of a projectile suspended from said member and vertically reciprocable with respect thereto, said element being adapted to be moved into predetermined proximity with the terrain, and means to limit the length of movement 145 of said element, said element being approximately the shape of half an elongated drop having a longitudinal flat face and a rounded back and an enlarged rounded lower end.
15. In a device for giving instruction in the

- conduct of artillery fire, a bead representing the appearance of a projectile burst under varying conditions, said bead being approximately the shape of half an elongated drop having a longitudinal flat face and a rounded back and an enlarged rounded lower end, said flat face being surfaced to simulate the appearance of an air burst, said rounded end being surfaced to simulate the appearance of a graze burst, a suspension wire carrying said bead, and a hinge connection of said bead upon said wire, said hinge including stop means to hold said bead suspended with its flat face inclined nearly to the vertical, but allowing said back to rest flat on the terrain-
10 representing means when not suspended.
- 15 16. In a device for giving instruction in the conduct of artillery fire, a bead representing the appearance of a projectile burst under varying conditions, a suspension wire carrying said bead, said bead having a flat face and an enlarged rounded lower end, and a hinge connection between said bead and said wire whereby said flat face is exposed to view when the bead is suspended and said lower end is exposed to view when the bead is supported from below.
- 20 17. In combination, in an apparatus for giving instruction in the conduct of artillery fire, a single bead having two exposable faces one of which is colored as an air burst and the other of which is colored as a graze burst and means for exposing the first named face when the bead is in the air and for exposing the second named face when said bead comes into contact with a material object.
- 25 18. In a device for giving instruction in the conduct of artillery fire, a bead adapted to represent the appearance of a projectile burst in air or in graze, a representation of a terrain, a framework above said terrain, a screen hiding said framework but permitting a view of the terrain, means for supporting said bead from said framework, and a spring in conjunction with said supporting means, said spring normally holding said bead concealed by said screen.
- 30 19. In a device for giving instruction in the conduct of artillery fire, a cross bar mounted on a pair of convex rocker shoes, a slide having a bifurcated base and having a portion offset from said bar adapted slidably to receive said bar, a rod mounted on the offset portion of said slide, a handle member slidable on said rod, a wire suspended from said handle member and in a plane radial to said rocker shoes, and means carried by said wire simulating the appearance of the burst of an artillery projectile, said handle being adapted to move said wire to position said simulating means in given relation to said slide and said rod.
- 35 20. In a device for giving instruction in the conduct of artillery fire, in combination with means representing a terrain and including a pair of parallel range arms, means mounted on said arms comprising a cross-bar and a shoe having a convex bottom surface mounted on each end of said cross-bar, said shoes having their convex surfaces slidably mounted on said arms, respectively, means for rocking said shoes on said arms, a stop comprising a surface formed to a probability curve of dispersion in range, and an element movable with one of said shoes adapted to contact with said stop.
- 40 21. In a device for giving instruction in the conduct of artillery fire, in combination with means representing a terrain and including a pair of parallel range arms, means mounted on said arms comprising a cross-bar and a shoe having a convex bottom surface mounted on each end of said cross-bar, said shoes having their convex surfaces slidably mounted on said arms, respectively, means for rocking said shoes on said arms, a stop comprising a surface formed to a probability curve of dispersion in range, and a cylinder being pivoted for free rotation, and an element movable with one of said shoes adapted to contact with said stop.
- 45 22. In a device for giving instruction in the conduct of artillery fire, means representing a terrain, and means associated with said first-mentioned means for indicating the longitudinal, lateral, and elevational location with respect to said terrain of the burst of projectiles thrown from a hypothetical piece at any given aim, said last-mentioned means including a bead simulating the appearance of a projectile burst, means for moving said bead into a position in proximity to said terrain to simulate the explosion of a projectile and mechanical means for controlling said position of said bead in mathematical accordance with ballistic probabilities of dispersion in range and in height of burst.
- 50 23. In a device for giving instruction in the conduct of artillery fire, a cross-bar mounted on a pair of convex rocker shoes, a slide having a bifurcated base and having a portion offset from said bar adapted slidably to receive said bar, a plate perpendicular to said cross-bar and slidably mounted on an upwardly and forwardly inclined element of said offset portion, an index means for placing said plate in relation to said inclined element to represent a fuze corrector setting, means for holding said plate and said element in fixed relative position, an upright member mounted on said plate, and means carried by said upright member comprising a suspension movable in a generally vertical direction, and an element on the lower end of said suspension for simulating the appearance of the burst of an artillery projectile.
- 55 24. In a device for giving instruction in the conduct of artillery fire, means representing a terrain, a member movable by an operator relative to said terrain in response to a student's orders, a single bead carried by said member for indicating selectively either "graze bursts" or "air bursts" relative to the terrain, a variable stop for governing the movement of said bead, the variations of said stop being representative of ballistic variation probabilities in height of burst, a support carrying said stop, said support being vertically movable to positions representing selected angles of site, and means for maintaining said support at any selected representative position.
